J. A. FROSSARD.

SCRAPER FOR PAPER CALENDERING ROLLS OR THE LIKE.

APPLICATION FILED APR. 16, 1918.

1,299,930.

Patented Apr. 8, 1919.

Inventor:

John A. Frossard
By his attorney,
Parker S. Gooding.

UNITED STATES PATENT OFFICE.

JOHN A. FROSSARD, OF EAST PEPPERELL, MASSACHUSETTS.

SCRAPER FOR PAPER-CALENDERING ROLLS OR THE LIKE.

1,299,930.

Specification of Letters Patent.

Patented Apr. 8, 1919.

Application filed April 16, 1918. Serial No. 228,954.

To all whom it may concern:

Be it known that I, JOHN A. FROSSARD, a citizen of the United States, residing at East Pepperell, in the county of Middlesex and 5 State of Massachusetts, have invented new and useful Improvements in Scrapers for Paper-Calendering Rolls or the like, of which the following is a specification.

This invention relates to improvements in 10 scrapers, sometimes called "doctors," for paper calendering machines or the like.

The object of the invention is to provide 15 a scraper of simple construction adapted to be applied to various types of calendering machines and having means for adjusting the scraper at points uniformly spaced throughout the length thereof so as to provide a uniform pressure, thus preventing any injury to the roll by scoring or other- 20 wise.

Another object of the invention is to provide means for applying a variable tension 25 to said scraper against the calendering roll in such a manner that the pressure throughout the length of said scraper will be uniform.

The invention consists in the combination and arrangement of parts set forth in the following specification and particularly 30 pointed out in the claims.

Referring to the drawings:

Figure 1 is a plan view of a device embodying my invention shown in connection with a calendering roll, the side frames of 35 the machine being shown in section and portions of the scraper and its supporting means being broken away to save space in the drawings.

Fig. 2 is a vertical section taken on the 40 line 2-2 of Fig. 1.

Fig. 3 is a vertical section taken on the line 3-3 of Fig. 1, illustrating the tension regulating means.

Like numerals refer to like parts throughout the several views of the drawings.

In the drawings, 1 and 2 indicate a pair of calendering rolls of a paper calendering machine embodying the usual side frames 3 and 4, which side frames serve as guides 50 for journal boxes 5 and 6 within which the rolls 1 and 2 are journaled to rotate.

In machines of this character, the paper is fed through the rolls thereof at a very high rate of speed and during its passage, 55 the surfaces of the paper are calendered and

it is therefore essential that the surfaces of the rolls be kept very smooth and clean, otherwise the marks would show upon the paper.

To keep the rolls clean, scrapers have been 60 used more or less extensively, said scrapers being often called "doctors" which are yieldingly maintained in contact with the surfaces of said rolls and scrape therefrom any portions of the paper which may ad- 65 here thereto.

Furthermore, these scrapers or "doctors" are of great advantage in starting the paper 70 through the rolls for unless some such device is employed, the ends will sometimes stick to the rolls and owing to the speed 75 at which the rolls are turning a large amount of paper will be wound about the rolls before the same can be stopped. This amount will, therefore, be wasted. 75

In the present case, a scraper is employed which embodies in its construction a resilient blade 7 arranged at the rear of the rolls 1 and 2 and in contact with the upper roll of the pair and at a short distance back of the contacting portions of said rolls. This blade is preferably secured between two parallel strips of metal 8 and 9 which are held together by screws 10 and constitute a holder for said blade. Said 80 strips 8 and 9 are separated at the rear edges by a narrow strip 11 inserted therebetween which is preferably equal in thickness to the blade 7 so that the forward edges of said strips will lie parallel against opposite faces 90 of said blade and securely hold the same therebetween, said blade being inserted between said strips as far as the screws 10 will permit. 95

A supporting bar, preferably an angle bar 12, is disposed parallel with the rolls 1 and 2 and at the rear of the scraper blade 7. A leg 13 of said angle bar is directed toward the contacting portions of the rolls 1 and 2 while the other leg 14 of said angle bar is directed downwardly. This bar has secured at opposite ends, studs 15 which constitute pivots for said bar and permit the same to be rocked slightly relatively to the roll. 100

Interposed between the holder for the 105 scraper 7 and the leg 13 of said bar are a plurality of supporting elements 16 arranged at substantially equal distances apart throughout the length of the scraper, and these supporting elements are preferably 110

narrow strips of steel which are preferably riveted to the end strip 9 of said holder by rivets 17. These supporting elements are attached to the leg 13 of said angle bar in such a way that a limited pivotal movement thereof will be permitted in a plane disposed substantially at right angles to the axes of the rolls 1 and 2.

This is accomplished preferably by securing the supporting elements 16 to the forward edge of the leg 13 of said angle bar by means of screws 18, said supporting elements extending beyond said screws where they are each engaged by a set screw 19 having screw threaded engagement with the angle bar 12, and by moving the screw 19 downwardly the supporting element engaged thereby may be rocked about the screw 18 which constitutes the fulcrum thereof and thus raise the end of the scraper 7 which engages the roll.

By means of these individual adjustments, different portions of the scraper may be brought nearer or moved farther away from the surface of the roll 1, or, in other words, a uniform pressure may be exerted by said scraper against all portions of the roll 1 and prevent the scoring or injuring of the roll at any point in the length thereof. The angle bar 12 is adjustably mounted relatively to said roll to move either vertically or horizontally toward and from the roll 1.

To accomplish this result, a pair of slides 20 are arranged in brackets 21 transversely, of which said slides are adapted to move toward or from the roll 1. The brackets 21 are, in turn, mounted upon parallelly disposed guide members 22, 22 secured to the side frames 3 and 4. The parallelly disposed members are disposed vertically upon the frames 3 and 4 and are separated from said frames by separators 23 which provide sufficient room between said members 22 and said frames for the heads 24 of screws 24' which are arranged between the parallel members 22 and secure the brackets 21 to said parallel members.

A plurality of sets of holes 25 are provided in the brackets 21 so that said brackets 50 may be moved transversely of said parallel members to vary the positions thereof relatively to the rolls 1 and 2. The brackets 21 have grooves 26, within which the slides 20 are arranged to assist in positioning said slides upon said brackets. A screw 27 is provided for each of said slides by means of which said slides may be secured to their respective brackets.

It is desirable that means be provided for 60 applying a yielding pressure to the scraper 7, and this pressure is preferably accomplished, in the present instance, by means including a torsional spring 28 constructed in the form of an angle bar and secured at a 65 plurality of points by screws 29 to the rear

of the angle bar or supporting member 12, said spring being disposed longitudinally of said bar.

The screws 29 secure one end of said spring to said supporting member while the 70 opposite end is free to be deflected relatively to the angle bar 12 and the deflecting action thereof applies the necessary pressure to the scraper 7. To deflect said spring, a lever 30 is provided, said lever being pivotally 75 mounted upon the stud 15 adjacent to the free end of said spring, and this lever has a slot 31 formed therein to receive a stud 32 secured to the free end of said spring.

Means are provided for holding the lever 80 30 in the desired positions to maintain said spring under tension, said means preferably including a latch 33 pivoted at 34 to the free end of said lever 30. The latch 33 moves upon its pivot between lugs 35 on said lever 85 which withstand a greater portion of the pressure exerted thereon by said spring. This latch is adapted to engage suitably positioned lugs 36 formed upon the slide 20 adjacent thereto by a spring 37 which forces 90 the free end of said latch outwardly from said lever into alignment with one of said lugs 36.

To operate the lever 30 to vary the tension on the scraper 7, the latch 33 is pressed toward the handle of the lever 30, thus disengaging said latch from the lug 36 and deflecting the spring 37, and after said lever has been rocked about the pivoted stud 15 to accomplish the desired deflection of the 100 spring 28, the latch 33 may be released and will be forced outwardly in contact with one or the other of the lugs 36, thus retaining said lever in the desired position.

Having thus specifically described my invention what I claim and desire by Letters Patent to secure is:

1. In combination, a roll, a scraper extending substantially the length thereof arranged in contact with said roll, a supporting member for said scraper, and disposed substantially parallel with said roll, and means interposed between said scraper and said supporting member at predetermined distances apart throughout the length of said scraper, adapted to support said scraper.

2. In combination, a roll, a scraper arranged with one edge in contact with said roll, an angle bar disposed substantially parallel with said roll with one of the legs 120 thereof directed toward said roll, a plurality of supporting elements interposed between said scraper and said angle bar, and means for adjusting said supporting elements relatively to the leg of said angle 125 bar directed toward said roll.

3. In combination, a calendering roll, a resilient scraper arranged in contact with said roll, an angle bar disposed substantially parallel with said roll, one of the legs there- 130

of directed toward said roll, a plurality of blade supporting elements mounted upon the leg of said angle bar directed toward said roll, said supporting elements being arranged to rock in a plane at right angles to the axis of said roll, and means for moving said supporting elements independently of each other relatively to said angle bar.

4. In combination, a roll, a scraper arranged in contact with said roll, a supporting member pivotally disposed substantially parallel with said roll, a plurality of relatively movable supporting elements interposed between said scraper and said supporting member, means for rocking said supporting member upon its pivot to apply pressure to said scraper, and a torsional spring interposed between said supporting member and its operating means.

20 5. In combination, a roll, a scraper adapted to engage said roll, a supporting member for said scraper pivotally disposed in substantially parallel relation to said roll, a torsional spring secured at one end thereof to said supporting member, a lever pivotally mounted to rock about the axis of said supporting member, said lever having engagement with the other end of said spring, adapted to be rocked relatively to said supporting member to deflect said spring, and means for locking said lever in various positions relatively to said supporting member.

30 6. In combination, a roll, a scraper adapt-

ed to engage said roll, a supporting member for said scraper pivotally disposed in substantially parallel relation to said roll, relatively adjustable supporting elements interposed between said supporting member and said scraper disposed at uniform distances apart throughout the length of said scraper, a torsional spring attached to said supporting member, and means engaging said torsional spring adapted to deflect the same and to apply a variable pressure through said supporting elements to said scraper.

7. In combination, a pair of paper calendering rolls, a resilient scraper arranged in contact with one of said rolls, a supporting member for said scraper including an angle bar disposed with one leg thereof directed toward said rolls, the other leg of said angle bar extending downwardly, means for connecting said scraper with said first mentioned leg, and a reinforcing block secured to said other leg adapted to be engaged by paper which is being fed between said rolls and direct said paper downwardly therefrom.

In testimony whereof I have hereunto set my hand in presence of two subscribing witnesses.

JOHN A. FROSSARD.
